UNITED STATES PATENT OFFICE.

JOHN VAN DEVELDE, OF CLEVELAND, OHIO.

PAPER BARREL.

SPECIFICATION forming part of Letters Patent No. 651,517, dated June 12, 1900.

Application filed March 15, 1900. Serial No. 8,742. (No model.)

To all whom it may concern:

Be it known that I, JOHN VAN DEVELDE, a citizen of the United States of America, and a resident of Cleveland, in the county of Cuyahoga and State of Ohio, have invented certain new and useful Improvements in Paper Barrels, of which the following is a specification.

This invention relates to paper barrels; and it consists in the new construction and adaptation of the hoops to the barrel, whereby greater strength and stiffness is obtained, substantially as hereinafter described, and pointed out in the claim.

15 The nature and objects of the invention will fully appear when considered in connection with the accompanying drawings, in which—

Figure 1 is a vertical section of a portion of a barrel having my improvements, showing the peculiar construction of the barrel and application of the hoops for the purpose above stated. Fig. 2 is a transverse or horizontal section on line 2 2 on Fig. 1. Fig. 3 represents one of the hoops.

A represents the body of the barrel, which is made of sheet-paper by rolling the paper on rollers or mandrels designed for the purpose. As the paper is rolled on the mandrels 30 glue or any suitable adhesive material is applied for sticking the layers of paper together. The mandrel on which the paper is rolled has tapering grooves, as *a a*, formed in its surface from the ends toward the middle, and 35 the impression-roller, which works in conjunction with the mandrel, has corresponding ribs which act to impress the paper into the said grooves for the purpose of making tapering crimps in the cylindrical body for 40 reducing the diameter of the body from the middle to the ends for producing the bilge. On the mandrel, at the middle or bilge portion, is also made an annular groove B and on the impression-roller is made a corresponding 45 annular bead, which serve to produce an annular groove in the body of the barrel. On

one end of the mandrel is also made an annular groove C and on the impression-roller is also made an annular rib-bead, which serve to produce an annular groove in the body of the barrel near the end. These grooves are 50 for receiving the hoops.

D are the hoops, consisting of metal bars having a concavo-convex (in cross-section) rib *d*, designed to occupy the annular grooves 55 in the body of the barrel. These hoops have barbs *e e*, one on each end, and in one end a slot *f*. These hoops are applied and secured to the paper bodies by placing the ends having the slots *f* in the grooves B and C with 60 the barbs inward, and as the body is rotated the barbs are forced into the paper and the hoops rolled into the grooves, and at the completion of the revolution the end barb is inserted into the slot *f* and forced into the paper 65 and clenched on the inside, as seen in Fig. 2.

The fasteners for the head of the barrel consist of wires or flat strips of metal G and are held under the end hoops, being put in place as the hoop is being rolled on. The heads H, 70 which are also made of paper or may be of other suitable material, are inserted to place and rest on the shoulder formed by the annular groove C. Now the ends of the fasteners are bent over the chime of the barrel 75 and down onto the edge of the head, and thus fasten the heads in place, as shown in Fig. 1.

Having described my invention, what I claim is—

In a barrel formed of sheet-paper, an annular groove near one end, a corrugated hoop contained and secured in said groove, fasteners in said groove held by the hoop, and engaging the head, for fastening the same in the barrel, substantially as described. 85

Signed by me at Cleveland, Ohio, this 13th day of March, 1900.

JOHN VAN DEVELDE.
